(57) **CLAIM**

The ornamental design for a protective tablet case as shown and described.

DESCRIPTION

FIG. 1 is a front perspective view of the protective tablet case comprising the present invention;
FIG. 2 is a front elevation view thereof;
FIG. 3 is a rear elevation view thereof;
FIG. 4 is a right side view thereof;
FIG. 5 is a left side view thereof;
FIG. 6 is a top view thereof;
FIG. 7 is a bottom view thereof;
FIG. 8 is a bottom front perspective view thereof;
FIG. 9 shows the protective tablet case in an environment of use; and,
FIG. 10 shows the protective tablet case in an environment of use.
Broken lines shown in the drawings illustrate portions of the protective tablet case and form no part of the claimed design.

1 Claim, 8 Drawing Sheets
